*Primary Examiner — Phillip S Hyder**(74) Attorney, Agent, or Firm — Reinhart Boerner Van Deuren s.c.*(57) **CLAIM**

I claim the ornamental design for a cutting tool, as shown and described.

DESCRIPTION

FIG. 1 is a rear perspective view from above of an embodiment of the claimed design;
FIG. 2 is a front perspective view from below of the claimed design of FIG. 1;
FIG. 3 is a top view of the claimed design of FIG. 1;
FIG. 4 is a bottom view of the claimed design of FIG. 1;
FIG. 5 is a left view of the claimed design of FIG. 1;
FIG. 6 is a right view of the claimed design of FIG. 1;
FIG. 7 is a rear view of the claimed design of FIG. 1; and,
FIG. 8 is a front view of the claimed design of FIG. 1.
The broken lines in the drawings are for illustrative purposes only and form no part of the claimed design.
